US00D545248S

(12) **United States Design Patent** (10) **Patent No.:** **US D545,248 S**
(45) **Date of Patent:** **** Jun. 26, 2007**

(54) **TRUCK BUMPER**

(75) Inventors: **Gerald Jay Angelo**, Bellevue, WA (US); **Wayne K Simons**, Kent, WA (US); **Daniel R Kieffer**, Kirkland, WA (US); **Wallace A Peltola**, Sammamish, WA (US); **Daniel Farmer**, Coupeville, WA (US); **F. Erik Tuft**, Farmington Hills, MI (US)

(73) Assignee: **Paccar Inc**, Bellevue, WA (US)

(**) Term: **14 Years**

(21) Appl. No.: **29/265,490**

(22) Filed: **Aug. 31, 2006**

(51) **LOC (8) Cl. 12-16**

(52) **U.S. Cl. D12/169**

(58) **Field of Classification Search** D12/90-92, D12/86, 169, 196, 163; 296/180.1, 180.2; 293/102, 113, 115, 117, 120

See application file for complete search history.
